UNITED STATES PATENT OFFICE.

WALTER L. SIEWERS, OF WINSTON-SALEM, NORTH CAROLINA, ASSIGNOR TO THE
MALINE MILLS COMPANY, OF WINSTON-SALEM, NORTH CAROLINA, A CORPORA-
TION OF NORTH CAROLINA.

LADY'S UNDERGARMENT.

Application filed July 12, 1924. Serial No. 725,707.

To all whom it may concern:

Be it known that I, WALTER L. SIEWERS, citizen of the United States, residing at Winston-Salem, in the county of Forsyth and State of North Carolina, have invented certain new and useful Improvements in Ladies' Undergarments; and I do hereby declare the following to be a full, clear, and exact description of the invention, such as will enable others skilled in the art to which it appertains to make and use the same.

This invention relates to ladies' undergarments, and has for its object to provide a garment which will be constructed without waste of material as regards the main body of the garment. The main body of the garment is formed from a tubular member of substantially the same diameter throughout, and the same is slit in the middle at the front and back from the bottom thereof for a short distance thereabove, and is adapted to have a pair of connected pentagonal shaped gussets inserted in the slit and sewed therein to give the necessary width at the bottom of the garment to constitute the leg portions thereof.

The various novel features of the invention will appear from the detail description of the invention taken in connection with the accompanying drawings forming a part of this specification.

In the drawings, Figure 1 is a front elevation of my improved garment showing the pair of pentagonal shaped gussets in position therein.

Figure 2 is a rear elevation of my improved garment showing the pentagonal shaped gussets in position therein showing the pointed ends of the same extending upwardly to a higher point at the rear than at the front of the garment.

Figure 3 is a plan view of a pair of pentagonal shaped gussets used in my improved garment.

Figure 4 is a plan view of a single pentagonal shaped gusset used in my improved garment; and,

Figure 5 is a plan view of a slight modification of the pentagonal shaped gusset showing the same provided with a deeper notch.

Like characters of reference are used throughout the following specification and

the accompanying drawings to designate corresponding parts.

The garment is formed of a knitted tubular member of substantially uniform diameter throughout the length of the same, and constitutes a body portion 1 which has the conventional shoulder straps 2 attached to the upper portion thereof, and has the usual draw string 3 at the top of the garment.

The tubular body portion 1 is slit in the middle at the front and back from the bottom thereof for a short distance thereabove, the slit at the back of the body portion being extended up a slight distance above the slit at the front of the garment. My improved form of gusset comprises a pair of pentagonal shaped pieces of material 4 which are concavely notched as at 5. Two pieces of the material 4 will be sewed together at 6 with the notched portions of each piece adjacent each other, so that the completed gusset 7 will be formed as illustrated in Figure 3 of the drawings. The gusset 7 will be inserted in the slit formed at the bottom of the tubular body member 1 and the pointed end 8 of the gusset will be sewed at the apex of the slit at the back of the garment while the point 9 will be sewed at the apex of the slit at the forward part of the garment, while the adjacent sides of the gusset are sewed to the adjacent portions of the body member so that there will be considerably more room at the back of the leg portions than at the forward part thereof.

A modification of the gusset material is shown in Figure 5 and is designated at 10, and is provided with a deeper notch 11 so that additional room may be had in the leg portions of the garment.

From the foregoing description it will be apparent that the pieces of material forming the gusset of the garment will form the inner or adjacent portions of the leg portions of the garment, and as before mentioned provides a larger space at the back of the garment than at the front thereof.

The garment made in accordance with this invention can be readily manufactured at a minimum cost since it is merely necessary to slit the tube or body 1 and insert the pentagonal shaped gusset into the slits to pro-

vide the necessary and desired width at the bottom of the garment.

Many minor changes in detail of construction may be resorted to without departure 5 from the spirit of the invention.

I claim:—

In combination with a tubular bifurcated nether garment slit in the middle, at the front and back, from the bottom thereof for

10 a short distance thereabove, a substantially pentagonal crotch insert, composed of a pair of pentagonal elements, each of said elements having a re-entrant angle, such elements being stitched together along the edges forming

15 the re-entrant angle, thereby causing the resultant insert to be of substantially

pentagonal shape and warped so as to conform to the contour of the body adjacent the crotch, the seam produced by stitching such elements together running from front 20 to back of the garment transversely of the crotch, the insert being free from seams vertically of the legs, the insert extending at a relatively high point at the back of the garment to constitute a seat for the same, and the elements of such insert extending to the bottom of the leg portions of the garment and forming complementary parts thereof. 25

In testimony whereof I affix my signature.

WALTER L. SIEWERS.
